(57) **CLAIM**

The ornamental design for a IV lock box, as shown and described.

DESCRIPTION

FIG. 1 is a front perspective view of an embodiment of the IV lock box, in a first closed configuration;

FIG. 2 is a front elevation view of the FIG. 1 device in the first configuration;

FIG. 3 is a rear elevation view of the FIG. 1 device in the first configuration;

FIG. 4 is a right-side elevation view of the FIG. 1 device in the first configuration;

FIG. 5 is a left-side elevation view of the FIG. 1 device in the first configuration;

FIG. 6 is a top plan view of the FIG. 1 device in the first configuration;

FIG. 7 is a bottom plan view of the FIG. 1 device in the first configuration;

FIG. 8 is a front perspective view of the FIG. 1 device in a second open configuration;

FIG. 9 is a front elevation view of the FIG. 1 device in the second configuration;

FIG. 10 is a rear elevation view of the FIG. 1 device in the second configuration;

FIG. 11 is a right-side elevation view of the FIG. 1 device in the second configuration;

FIG. 12 is a left-side elevation view of the FIG. 1 device in the second configuration;

FIG. 13 is a top plan view of the FIG. 1 device in the second configuration; and,

FIG. 14 is a bottom plan view of the FIG. 1 device in the second configuration.

The broken line showing of parts of the drawings is included for the purpose of illustrating use and environment and forms no part of the claimed design.

1 Claim, 14 Drawing Sheets
